3 Sheets-Sheet 1

Fig. 1.

The diagram illustrates a complex electrical circuit with the following components and connections:

- Power Source:** A battery is connected to terminal **T** and terminal **108**.
- Switches and Contacts:** Terminals **108**, **110**, **112**, **114**, **115**, **116**, **117**, **118**, **119**, **120**, **121**, **122**, **123**, **124**, **125**, and **140** are connected to various points in the circuit.
- Relays:** Relays **101**, **102**, **103**, **104**, **105**, **106**, **107**, **108**, **109**, **110**, **111**, **112**, **113**, **114**, **115**, **116**, **117**, **118**, **119**, **120**, **121**, **122**, **123**, **124**, and **125** are used throughout the circuit.
- Indicators:** Indicators **A** and **S** are connected to terminals **108** and **110** respectively.
- Labels:** Labels **FS**, **108**, **110**, **112**, **114**, **115**, **116**, **117**, **118**, **119**, **120**, **121**, **122**, **123**, **124**, **125**, **140**, **A**, **S**, and **FS** are placed near their respective components.
- Wires:** Numerous wires connect the components, forming a complex network of paths.

3 Sheets-Sheet 2

Fig. 2.

Diagram illustrating a complex electrical circuit, likely a relay control system. The circuit is organized into several vertical columns and includes various components such as resistors, capacitors, and switches. Key labeled components include:

- Power source: 214
- Resistors: 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250.
- Capacitors: 133, 134, 135, 136, 137, 138, 139, 162, 163, 164, 165, 166, 167, 168, 169, 161.
- Switches: 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250.
- Other: 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250.

The circuit is labeled with 'T' and 'S' at the bottom, and 'Inventor' is written in the bottom right corner.

MACHINE SWITCHING TELEPHONE EXCHANGE SYSTEM

Filed Dec. 8, 1920

3 Sheets-Sheet 3

UNITED STATES PATENT OFFICE.

RAY L. STOKELY, OF FLORAL PARK, NEW YORK, ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Application filed December 8, 1920. Serial No. 429,164.

To all whom it may concern:

Be it known that I, RAY L. STOKELY, a citizen of the United States, residing at Floral Park, in the county of Nassau, State 5 of New York, have invented certain new and useful Improvements in Machine-Switching Telephone-Exchange Systems, of which the following is a full, clear, concise, and exact description.

10 This invention relates to telephone exchange systems employing machine switching and its object is to provide an improved circuit arrangement to take care of toll calls.

15 It is now the practice so far as applicant is aware, in case an automatic subscriber desires a toll call, for him to set up a connection over one or more selectors to a recording operator's position and give her the necessary information. This operator passes 20 the information to a toll operator who has access to what are known as toll switches with which is associated the necessary long distance transmission equipment. The toll

25 operator then selects the calling line by means of these toll switches, and causes the connection to be built up over toll lines to the distant exchange wherein the called line terminates. The selectors which the calling 30 party used in connecting his line with the recording operator's position are thus not used in the long distance connection between the subscribers.

35 This invention provides an arrangement wherein the switches used by the calling party in connecting his line with the recording operator's position may be used in the long distance connection between the subscribers, thus obviating the necessity of 40 the toll operator setting up a connection to the calling line.

45 In accordance with this invention, the trunks terminating at the recording operator's position and which are selectable by the calling subscriber from a certain level of a selector are provided with long distance transmission equipment and also terminate at a toll operator's position. A call extended to one of these trunks lights a lamp at the 50 recording operator's position. This operator extends the calling line to a cord at her position and connects her head set to the cord and thus to the seized trunk and ascertains the wants of the calling subscriber, whereupon the subscriber may restore his receiver,

the switches being held set under control of the recording operator. This operator may now communicate over an order wire with an outward toll operator at whose position the seized trunk also appears, and pass along 60 to such operator the required information. The toll operator now connects a toll cord circuit to the terminal of the seized trunk appearing at her position, which causes a disconnect signal to be given the recording 65 operator who thereupon disconnects the trunk from her position, the set switches being now controlled by the toll operator. When the recording operator passes the call to the toll operator, if the calling party is 70 on a party line, she presses one of a number of keys which connects the proper character of ringing current to the contacts of a relay, which relay is operated by the toll operator to signal the originating subscriber when she 75 has received a response from the distant subscriber. The extension of the calling line to a toll cord by the toll operator operates a relay to cut off the trunk from its terminals 80 at the recording operator's position, leaving between the toll position and the calling line the long distance transmission equipment 85 which is included in the trunk which the calling subscriber selected.

Referring to the drawings, Fig. 1 illustrates a calling line, a line switch, and a selector; Fig. 2 illustrates a recording trunk circuit, and Fig. 3 illustrates a toll operator's cord circuit, and Fig. 4 illustrates a recording operator's cord circuit.

90 The invention will be more readily understood from a description of the operations involved in setting up a connection. The subscriber at substation A in making a call closes the following circuit to operate the 95 line switch LS to seize an idle first selector FS; free pole of battery, slow relay 100, contact 101, tip side of the line, the substation loop, ring side of the line, contact 102 to ground. Relay 100 in attracting its 100 armature closes a circuit for the pull down winding 103 of the line switch which in the well-known manner, operates the line switch to seize a preselected first selector FS, whereupon impulse relay E¹ operates over the 105 substation loop. In attracting its armature relay E¹ operates slow relay F¹. Relay F¹ in attracting its upper armature closes a circuit for the holding winding 104 of the line switch, and in attracting its lower armature 110

prepares a circuit for the vertical magnet 105 of the first selector. While the circuit of the line relay 100 over the substation loop is opened when the line switch operates, this relay is slow to release and holds the pull down coil 103 magnetized until after relay F¹ operates and closes the circuit of the holding winding 104, in the well-known manner thus maintaining the line switch operated. The calling party now operates his sender S for the first digit of the code necessary to call a recording operator thus interrupting the circuit of the impulse relay E¹. Each time relay E¹ retracts its armature, an impulse is transmitted to the vertical magnet 105 in series with the slow relay G¹ to lift the brushes of the first selector to the level corresponding to the digit in question. When the sender restores, relay E¹ releases. When relay G¹ operated upon the first impulse it prepared a circuit for relay H¹ which was closed over off normal contact 106 on the first step of the selector shaft. This relay thereupon locked up over the following circuit: free pole of battery, relay H¹, conductor 107, contact 106, conductor 114, armature and back contact of rotary magnet 108, uppermost armature and front contact of relay H¹, conductor 109 to ground at the lowermost armature of relay D¹. When the slow relay G¹ releases at the termination of the impulses, rotary magnet 108 is energized over the inner armature of relay H¹, normal contact of relay G¹, upper armature and front contact of relay F¹ to ground and rotates the set of brushes onto the first trunk. At the end of the stroke of the rotary magnet, the locking circuit of relay H¹ is opened, which relay in releasing releases magnet 108. The brushes are now in engagement with the first trunk in the selected group. If this trunk is busy, a ground is present on the test multiple 110 and this ground is transmitted over the test brush 111, conductor 112, uppermost armature and back contact of relay D¹, conductor 113, armature and back contact of the rotary magnet, conductor 114, contact 106, relay H¹, free pole of battery. Relay H¹ thereupon operates and again locks itself over the circuit previously traced to ground at the lowermost armature and back contact of relay D¹. In attracting its lower armature, relay H¹ again energizes the rotary magnet which rotates the brushes on to the next trunk. Assuming this trunk to be idle, no ground is present on the test multiple 110 and consequently relay H¹ remains deenergized, after its locking circuit is opened by magnet 108. Switching relay D¹, however, is now operated over the following circuit: free pole of battery, relay H¹, conductor 107, contact 106, conductor 114, armature and back contact of magnet 108, conductor 113, relay D¹, conductor 115 to ground at the upper armature and front contact of relay F¹. Relay H¹ is marginal and does not operate in this circuit. Relay D¹, however, operates and places a direct ground from the upper armature of relay F¹, the uppermost armature of relay D¹, conductor 112, brush 111 to the test multiple of the seized trunk to cause the same to test busy to other selectors. Relay D¹, in attracting its inner armatures, extends the tip and ring conductors of the calling line to the tip and ring conductors of the trunk which terminate in the talking brushes 118 and 119. The tip, ring and sleeve conductors on the left of Fig. 2 are shown dotted, which indicates the omission of a selector or selectors. In practice the trunk shown in Fig. 2, would preferably terminate in a level of a third selector and the subscriber, therefore, will dial a code of three digits to secure one of the trunks shown in Fig. 2, or in other words to secure a recording operator. Assuming now that the calling line has been extended to an idle trunk shown in Fig. 2, relay 200 thereat operates over the calling line circuit, and in attracting its left armature energizes a slow relay 201. Relay 201 in attracting its left armature applies ground to the sleeve wire 202 to maintain the cut-off winding 104 of the line switch and switching relay D¹ energized to prevent premature release in the well-known manner. Relay 201 at its right armature applies tone from the source 203 to the calling line to indicate to the calling subscriber that his call is being properly extended. Relay 200 in attracting its right armature, lights the calling lamp 204 associated with the jack 205 of the seized trunk located at the recording operator's position. In response to the lighting of this lamp, the recording operator inserts the plug 400 in the jack 205 which causes the operation of relays 401, 206 and 207. Relay 401 in operating energizes relay 402 which extends the calling line to the operator's telephone circuit through the normal contacts of key 403. Relay 206 in operating applies ground to the sleeve wire 202 to hold the line switch and selectors set, thus placing the control of the release of these switches under the joint control of the calling party and the recording operator. Relay 207 in attracting its middle armature locks itself to the grounded sleeve wire 202. In attracting its innermost armature this relay extinguishes the calling lamp 204. In attracting its outermost armature, this relay disconnects the ringing tone from the calling line, thus informing the calling subscriber that his call has been answered by the recording operator. The recording operator may now listen for a tone from the tone coil 130 individual to the class of lines 130

to which calling line belongs to indicate to her the class of service to which the calling subscriber is entitled. The tone circuit may be traced as follows: free pole of battery, 5 secondary winding 120 of the tone coil, holding winding 104 of the line switch, line switch contact 122, uppermost armature and front contact of relay D', sleeve conductor 112, brush 111, multiple 110, upper winding 10 of tone transformer 208 to ground at the left armature and front contact of relay 201. This tone is transmitted by induction over the following circuit to the operator's headset; left side of the lower 15 winding of the coil 208, conductors 209, 210, tip of the jack 205, tip of the plug 400, upper armature and front contact of relay 402, normal contacts of key 404, condenser 405, normal contact of key 403 through the 20 operator's telephone set, normal contact of key 403, condenser 406, normal contact of key 404, ring of plug 400, ring of jack 205, normal contact of relay 211, condenser 212, retardation coil 213 to the other 25 side of the lower winding of the tone transformer 208. It will be understood that the character of the tone or the absence of tone will indicate to the recording operator to which class the calling line belongs. 30 Depending upon the information thus acquired, the operator will either refuse toll service to the calling subscriber or may give him toll service after approval by a supervisor, or may give him toll service without 35 such approval. The recording operator will now depress key 214 which causes the tone to be removed and connects the trunk conductors 224, 225 through to her headset, in order that she may communicate 40 with the calling party. The operation of key 214 energizes relay 211, which attracting its inner armatures extends the tip and ring conductors of the trunk to which the calling line is now extended through to the 45 tip and ring conductors of the jack 205 in which the plug 400 is inserted as described. The attraction of the armature 216 of relay 211 releases relay 206, but before relay 206 releases, another ground is applied over conductors 245, 246, to the sleeve wire 202 by 50 armature 217 of relay 211. Relay 211 in attracting its armature 216 locks up to the sleeve wire 218 now connected to battery through the relay 401. The recording operator now talks with the calling subscriber and secures from him the necessary information as to the line desired as well as his own number. She now communicates over an order wire (not shown) with an outward toll operator while retaining plug 400 in jack 205. The outward toll operator now inserts plug 300 into jack 220. This jack is also individual to the trunk shown in Fig. 2, but appears at the toll operator's position. The insertion of plug 300 into jack 220 op- 55 erates relay 221, which in attracting its inner armatures, applies interrupted current from source 223 to the trunk leading to the recording operator's position to give her a peremptory disconnect signal. The circuit 60 is as follows: free pole of battery, inter- 70 rupter 223, armature and front contact of relay 221, armature and front contact of relay 211, trunk conductor 210, tip of jack 205, tip of the plug 400, upper armature of 75 relay 402, normal contact of key 404, lower armature of relay 402, relay 408, normal contact of key 404, lower talking conductor, ring of the plug 400, ring of the jack 205, lower talking conductor, armatures and 80 front contacts of relay 211 and 221 to the other pole of the battery. Relay 408 thus flashes the lamp 409 to indicate to the recording operator that the toll operator has plugged into the trunk, whereupon the 85 recording operator removes the plug 400 from the jack 205. The operation of the relay 221 disconnects the talking conductors 224 and 225 from the talking conductors 226 and 227 leading to the jack 205. The attraction of the uppermost armature of relay 221 and the releasing of relay 211 due to the withdrawal of the plug 400 from the jack 205 again operates the relay 206 to maintain 90 ground on the sleeve wire 202 to prevent release. Thus the control of the release is now jointly controlled by the subscriber and the toll operator. 95

The toll operator now proceeds to build up the connection to the desired line over the plug 301 and jack 307. The circuits involved are not shown since they are well known. When the operator at the distant exchange has secured the desired party she rings back on the toll line 360, 361 which 100 operates alternating current relay 362. This relay opens the circuit of a slow relay 363 which relay as well as sleeve relay 367 was operated when the plug 301 was inserted in jack 307. Relay 363 in releasing lights lamp 105 364. The toll operator observing the lighted lamp knows that the toll call has been built up and proceeds to signal the subscriber at sub-station A who originated the call, by actuating her ringing key 305 which operates the alternating current relay 240 in the trunk, Figure 2. This relay in operating operates relay 227, which in turn in attracting 110 its armatures applies ringing current to the calling line to ring the bell at the calling substation to inform the subscriber that the party he desires has responded. It will be understood that in the meantime substation A is not selectable in the local connector 115 multiples due to the ground applied by way of wire 112, to the connector multiple 140 in accordance with standard practice. The removal of the receiver by the originating subscriber again operates relay 200, which removes battery and ground from the trunk 120 125 130

conductors 224 and 225, releasing the relay 302 in the toll cord, Figure 3. The release of this relay extinguishes the lamp 303 thus informing the toll operator that the subscriber has removed his receiver. The subscribers may now converse. Talking current is fed to the substation of the originating subscriber over the windings of relay 200 and repeating coil 228. Talking current is fed to the distant station from the office in which such station terminates, through the windings of a similar repeating coil, in accordance with standard long distance practice.

15 The calling subscriber upon the termination of the conversation replaces his receiver. This causes the relay 200 to close its back contacts; again applying battery and ground to the trunk conductors 224 and 225 to operate the relay 302 in the toll cord, which relay in operating again lights the lamp 303 to serve as a disconnect signal to the toll operator, whereupon she removes the plug 300 from the jack 220 and by means 25 of her ringing key 306 rings out on the toll line 360, 361 to give a disconnect signal to the distant operator.

Removal of the plug 300 from the jack 220 releases relay 221 which releases relay 306. Relay 206 in retracting its armature, removes ground from the sleeve conductor 202 thus causing the release of the line switch and the selectors. The release of relays 221 and 207 restores the normal connection of the trunk 224 and 225 with the jack 205 at the recording operator's position.

Three relays 230, 231, and 232 are shown and keys 233, 234 and 235 are provided for party line working to permit the recording operator to pick out the particular character of ringing current required, and prepare a circuit for impressing such current on the originating subscriber's line, which circuit is closed, by the toll operator as described. The operation of any of these keys operates the corresponding relay which thereupon locks up through a key 241 to ground on the sleeve wire 202, the operated relay connecting the proper generator to the front contacts of the relay 250 which is operated when the toll operator actuates her ringing key 305 to signal the calling party when the distant called party has answered. The key 241 is provided to restore the setting if the operator has pressed the wrong key.

What is claimed is:

1. In a telephone system, the combination of subscribers' lines, a trunk line having long distance transmission equipment included therein, two positions at each of which said trunk terminates, a signal for said trunk at one of said positions, automatic switches for extending a subscribers' line to said trunk, means for thereupon operating said signal, a cord circuit at the posi-

tion where the signal is located, means for associating the said cord circuit with said trunk, a cord circuit at the other position, means for associating the same with said trunk and automatically disconnecting the first cord circuit therefrom, and means controlled from said other position for extending the call in the direction of the desired line.

2. In a telephone system, the combination of subscribers' lines, a trunk line having long distance transmission equipment included therein, two positions at each of which said trunk terminates, a signal for said trunk at one of said positions, automatic switches for extending a subscribers' line to said trunk, means for thereupon operating said signal, a cord circuit at the position where the signal is located, means for associating the said cord circuit with said trunk, a cord circuit at the other position, means for associating the same with said trunk and automatically disconnecting the first cord circuit therefrom and for transmitting a disconnect signal to said first position, and means controlled from said other position for extending the call in the direction of the desired distant line.

3. In a telephone system, the combination of subscribers' lines, a trunk line having long distance transmission equipment included therein, a recording operator's position wherein said trunk terminates, a toll operator's position wherein said trunk also terminates, a signal at said recording operator's position for said trunk, automatic switches for extending a subscriber's line to said trunk, means for thereupon operating said signal, a cord circuit at said recording operator's position, means for associating the same with said trunk, a cord circuit at the toll operator's position, means for associating the same with said trunk, and means actuated thereby for disconnecting the trunk from the recording operator's position and for giving her a disconnect signal.

4. In a telephone system, the combination of subscribers' lines, a trunk line having long distance transmission equipment included therein, a recording operator's position wherein said trunk terminates, a toll operator's position wherein said trunk also terminates, a signal at said recording operator's position for said trunk, automatic switches for extending a subscriber's line to said trunk, means for thereupon operating said signal, a cord circuit at said recording operator's position, means for associating the same with said trunk, a cord circuit at the toll operator's position, means for associating the same with said trunk, means actuated thereby for disconnecting the trunk from the recording operator's position and for giving her a disconnect signal, and means

controlled from the toll position for extending the call in the direction of the desired distant line.

5. In a telephone system, the combination of subscribers' lines, a trunk line having long distance transmission equipment included therein, a recording operator's position wherein said trunk line terminates, a toll operator's position wherein said trunk line also terminates, a signal at said recording operator's position for said trunk, automatic switches for extending a subscriber's line to said trunk, means for thereupon operating said signal, a cord circuit at said recording operator's position, means for associating the same with said trunk, a plurality of sources of ringing current, keys controlled by said recording operator for preparing the circuit to associate one of said sources with said trunk, a cord circuit at the toll operator's position, means for associating same with said trunk, means actuated thereby for disconnecting the trunk from the recording operator's position and for 25 giving her a disconnect signal, and means controlled by the toll operator for closing said prepared ringing circuit.

6. In a telephone system, the combination of subscribers' lines, a trunk line having long distance transmission equipment, included therein, a recording operator's position wherein said trunk line terminates, a toll operator's position wherein said trunk line also terminates, a signal at said recording operator's position for said trunk, automatic switches for extending a subscriber's line to said trunk, means for thereupon operating said signal, a cord circuit at said recording operator's position, means for associating the same with said trunk, a source of ringing current, a key controlled by said recording operator for preparing the circuit to associate said source with said trunk, a cord circuit at the toll operator's position, means for associating same with said trunk, means actuated thereby for disconnecting the trunk from the recording operator's position and for giving her a disconnect signal, and means controlled by the toll operator for closing said prepared ringing circuit.

7. In a telephone system, the combination of subscribers' lines, a trunk line having long distance transmission equipment included therein, a recording operator's position wherein said trunk terminates, a toll operator's position wherein said trunk also terminates, a signal at said recording operator's position for said trunk, automatic switches for extending a subscriber's line to said trunk, means for thereupon operating said signal, a cord circuit at said recording

operator's position, means for associating the same with said trunk, tone sources associated with the calling lines, a circuit including the calling line source, and said cord circuit closed when the cord circuit is associated with the trunk, a key for opening said circuit, a tone source associated with the trunk, a circuit including said source and the calling line which is closed when the calling line is extended to said trunk, means actuated by the operator in responding to the call for opening said last tone circuit, a cord circuit at the toll operator's position, means for associating the same with said trunk, and means actuated thereby for disconnecting the trunk from the recording operator's position and for giving her a disconnect signal.

8. In a telephone system, the combination of subscribers' lines, a trunk line having long distance transmission equipment included therein, a recording operator's position wherein said trunk terminates, a toll operator's position wherein said trunk also terminates, a signal at said recording operator's position for said trunk, a line switch and a plurality of selector switches adapted to be set by the calling subscriber to select said trunk, means for thereupon operating said signal, means controlled by the calling subscriber for releasing said switches, a cord circuit at said recording operator's position, means for associating the same with said trunk, and for transferring the control of release of said switches to the operator, a cord circuit at the toll operator's position, and means for associating the same with said trunk and for transferring the control of the release of said switches to said toll operator and for disconnecting the trunk from the recording operator's position and for giving her a disconnect signal.

9. In a telephone system, the combination of subscribers' lines, a trunk line, two positions at each of which said trunk terminates, a signal for said trunk at one of said positions, means for extending a subscriber's line to said trunk and operating said signal, a connecting circuit at the position where the signal is located, means for associating said connecting circuit with said trunk, a connecting circuit at the other position, means actuated by the association of the second connecting circuit with said trunk for disconnecting the first connecting circuit therefrom, and means controlled from said other position for extending the call in the direction of the desired line.

In witness whereof, I hereunto subscribe my name this 2nd day of December A. D., 1920.

RAY L. STOKELY.
